DISCHARGE HEAD FOR HAND PUMPS

Wallace F. Magers, Leawood, Kans., assignor to Cook Chemical Company, Kansas City, Mo., a corporation of Missouri

Filed June 26, 1969, Ser. No. 17,888

Term of patent 14 years

Int. Cl. D23—01; D8—03

U.S. Cl. D23—14

FIG. 1 is a top and rear perspective view showing one side of the discharge head for hand pumps;

FIG. 2 is a bottom and rear perspective view showing the opposite side thereof;

FIG. 3 is a top plan view;

FIG. 4 is a bottom view;

FIG. 5 is an end view; and

FIG. 6 is a cross-sectional view taken on line 6—6 of FIG. 5.

I claim:

The ornamental design for a discharge head for hand pumps, as shown.
